UNITED STATES PATENT OFFICE.

WILLIAM T. BELL, OF CONCORD, NEW HAMPSHIRE.

LINK MAT.

Application filed January 19, 1925. Serial No. 3,295.

The invention pointed out by the claims of this application is an improvement on my Patent No. 1,448,907, dated March 20 1923, and is embodied in improved connections between the cylindrical wire pintle tie-rods and the flat-sided stiffener rods disclosed by said patent, whereby the strength and durability of the mat, particularly at its corner portions, are materially increased.

10 Of the accompanying drawings forming a part of this specification,—

Figure 1 is a fragmentary plan view, showing an end portion of a link-mat embodying the present invention.

15 Figure 2 is an edge view of the same.

Figure 3 is a perspective view of the flat-sided stiffener rod shown by Figure 1.

20 Figure 4 shows in perspective, an end portion of the cylindrical wire pintle rod shown by Figure 1, and one of its connecting arms.

Figure 5 shows in perspective, a portion of the stiffener rod and a portion of the pintle rod engaged therewith.

25 Figure 6 is a section on line 6—6 of Figure 1.

Figure 7 is an enlarged section on line 7—7 of Figure 5.

The same reference characters indicate the same parts in all of the figures.

30 The end portion of the mat shown by Figures 1 and 2, includes oblong links 12, usually of sole leather, arranged in transverse rows of groups, the groups of each row alternating with and overlapping the groups of the next

35 row. The mat portion shown includes, in addition to the end groups of links 12, intermediate shorter spacing links 13, of the same material as the links 12.

40 The links are provided with orifices receiving transverse metal tie-rods 14 and 15, on which the links are strung. The tie-rods 14 are of cylindrical wire and are bent and extended to form connecting arms 16. The tie-rods 15 are flat-sided and oblong in cross section, so that they constitute stiffener rods, which are adapted to be engaged with terminal portions of the connecting arms 16.

45 The construction thus far described is identical with that disclosed by my patent above mentioned. The engagement of the connecting arms 16 with the stiffener rod 15 is effected in the patented mat, by curved hooks, constituting the terminal portions of the arms 16, and holes in the end portions 50 of the stiffener rod 15, and extending from side to side thereof, the hooks passing

through the holes and forming protuberances projecting from the flat sides of the stiffener rod. These protuberances require enlargements of the link orifices which receive the 60 end portions of the stiffener rod and the protuberances formed by the hooked portions of the arm terminals, so that there is a minimum thickness of wear-sustaining material between the protuberances and the external 65 surfaces of the links. The links are therefore undesirably weakened and liable to be worn down or through to the protuberances, until the corners of the mat present a frayed 70 appearance. I obviate this objection by connecting the terminal portions of the arms 75 16 with the end portions of the stiffener rods 15, as next described.

Figure 8 is a fragmentary plan view, showing an end portion of a link-mat embodying the present invention. In the end portions of the rods 15 I form transverse slots 20, opening on one of the 75 longitudinal edges of the rod. On the connecting arms 16 I form angular terminals including straight portions 21, adapted to bear on said longitudinal edge, and straight portions 22, adapted to project into the slots 80 20. When the portions 22 are inserted in the slots, the connecting arms and their terminals are substantially flush with the flat sides of the stiffener rod 15, as shown by Figures 5 and 7, there being no projection of 85 the terminals from the flat sides, so that the orifices 23 in the links 12, which receive the end portions of the stiffener rod and the terminal portions of the connecting arms, may be parallel sided slots, spaced from the 90 external surfaces of said links by wear-sustaining portions 12^a (Figure 6, of maximum thickness, and free from liability of being worn through from the external surfaces of 95 the links.

Although the terminal portions 22 may be retained in the slots 20 by the slots 23, I prefer to rigidly secure the terminal portions in the slots 20 by means such as solder 24, shown by Figure 7, the elongation of the slots and the portions 22 enabling a strong solder joint to be formed therebetween.

It is obvious that the portions 22 may be rigidly secured in the slots by other means, such as spot welding.

105 In assembling the members constituting the illustrated portion of the mat, the pintle rod 14 may at first be provided with a connecting arm 16 at one end only, for example the end shown by Figures 4 and 5 and at the left in Figure 1, the rod being straight between said arm and its opposite end, so that the

portion from which the other arm 16 is to be formed is in line with the main portion of the rod. The stiffener rod 15 may then be engaged with the angular terminal portion 21, 22 of the connecting arm already formed as shown by Figure 5, and secured by solder if desired. The two rods now connected at one end only extend side by side and are separated at the ends not shown by Figure 5, so that the links may be strung on said ends and moved along the rods until the desired number of links have been assembled. The links may then be compressed upon the rods by pressure forcing the links toward the arm 16, already formed, until they are displaced sufficiently to uncover the slot 20 at the right in Figures 1 and 3, the compressibility of the sole leather of which the links are made permitting this displacement. While the links are thus compressed, the right hand end of the rod 14 may be bent to form the other arm 16 and its angular terminal, and the right hand end of the stiffener rod may then be engaged with the terminal last formed, solder being used if desired. Finally the compressing pressure on the links may be released so that the links may expand to their normal thickness, the links at the right hand end covering the right hand end of the stiffener rod 15 and the terminal last formed on the rod 14.

I claim:

1. A link mat which includes links arranged in overlapping groups, and a pair of transverse tie-rods inserted in orifices in the rows of links at the end portions of the mat, one of the tie-rods being a flat sided stiffener of oblong cross section, provided with slots in its end portions, opening on the flat sides of the rods, while the other rod constitutes a pintle portion of cylindrical wire, hingedly connecting other rows of links, and angular arms bent from the pintle por-

tion and including terminals parallel with and secured in said slots, said end portions and flat sides being in the same plane, the arrangement being such that the said rods are interengaged, without forming projections on the flat sides of the stiffener rods, so that the orifices in the end links which receive the terminals of the angular arms, and the slotted portions of the stiffener rod, are spaced from the external surfaces of said links by wear-sustaining portions of maximum thickness, and free from liability to be worn through from their external surfaces. 55

2. A link mat which includes links arranged in overlapping groups, and a pair of parallel transverse tie rods inserted in orifices in the links, one of the tie rods being a flat-sided stiffener of oblong cross section, while the other rod constitutes a pintle of cylindrical wire, and has tie-rod connecting arms at its ends, the stiffener rod being provided with transverse slots located near its ends, and opening on one longitudinal edge, while the connecting arms are provided with angular terminal portions, bearing on said longitudinal edge and on the sides of the slots, the connecting arms and their terminals being substantially flush with the flat sides of the stiffener rod, so that the orifices in the links which receive the end portions of the stiffener rods and the angular terminals, are spaced from the external surfaces of said links by wear-sustaining portions of maximum thickness, and free from liability to be worn through from the external surfaces of the links. 70

3. A link mat as specified by claim 1, the terminal portions projecting into the slots being rigidly secured to the sides of the slots. 75

In testimony whereof I have affixed my signature.

WILLIAM T. BELL.
